UNITED STATES PATENT OFFICE.

LEVI DE MYERS, OF TOLEDO, OHIO.

DESIGN FOR A GAME-TABLE.

SPECIFICATION forming part of Design No. 33,271, dated September 25, 1900.

Application filed August 18, 1900. Serial No. 27,348. Term of patent 14 years.

To all whom it may concern:

Be it known that I, LEVI DE MYERS, a citizen of the United States, residing at Toledo, in the county of Lucas and State of Ohio, have produced a new and original Design for a Game-Table, of which the following is a specification.

The leading feature of this design consists in the design forming the subject-matter of the accompanying illustration, wherein—

Figure 1 is a perspective view of game-table embodying the features of the design. Fig. 2 is a top plan view of the same.

The design is characterized by a horizontal base or bed 1 with rounded corners 2 and an upstanding rail 3 disposed inside the perimeter of the said base or bed. The rail 3 has solid end portions 4 and elongated side openings 5, which form top bars 6, between the under edges of which and the base or bed below a series of vertical pillars 7 are interposed in longitudinal alinement, the bases of the pillars being circular, as at 7, the portions above being curved and intermediately en-

larged, as at 8. From the base or bed at an intermediate point a plurality of vertically-extending cylindrical projections 9 are located, and at one end is a scalloped elevated member 10. From the center of the same end a projection 11 extends outwardly and is continued inwardly over the member 10 and slotted at its inner end. Depending from the base or bed 1 are circumferentially-grooved legs 12, those at one end being shorter than the others.

Having thus described the invention, what is claimed as new is—

The design for a game-table, herein shown and described.

In testimony that I claim the foregoing as my own I have hereto affixed my signature in the presence of two witnesses.

LEVI ^{his} X DE MYERS.
